UNITED STATES PATENT OFFICE.

JOHN A. MOORE, OF LOUISVILLE, KENTUCKY, ASSIGNOR TO THE MENGE COMPANY,
OF LOUISVILLE, KENTUCKY, A CORPORATION OF NEW JERSEY.

KNOCKDOWN CRATE.

Application filed February 14, 1924. Serial No. 692,761.

To all whom it may concern:

Be it known that I, JOHN A. MOORE, a citizen of the United States, residing at Louisville, in the county of Jefferson and State of Kentucky, have invented certain new and useful Improvements in Knock-down Crates, of which the following is a specification.

This invention pertains to an improved knock-down shipping crate, the construction and advantages of which will hereinafter appear.

The main object of the invention is to provide a knock-down crate which may be readily brought to its assembled position and locked in such position with the top open, whereby the goods may be readily packed or placed within the open crate or the cover raised after its receipt by the consignee for the purpose of displaying the goods or contents. A further object of the invention is to provide means for temporarily holding the front and back of the crate, the ends, and the bottom thereof, in their set-up position, such means being readily manipulated in bringing the crate to form, and as readily removed when it is desired to knock down the crate. A still further object of the invention resides in the provision of means for covering such temporary crate element sustaining means when the cover of the crate is closed and secured for shipment.

The invention is illustrated in the annexed drawings, wherein—

Fig. 1 is a perspective view of the crate set up and with the lid thrown to partially open position;

Fig. 2 a similar view showing the top closed and secured in place;

Fig. 3 a like view showing the crate in its outfolded position and with the two end members removed;

Fig. 4 a bottom plan view, broken away, showing the continuous binding strip which holds the various sections together and forms a hinged element for such sections;

Fig. 5 a detail perspective view illustrating the manner in which the sustaining or setting-up hook or element is attached to the batten element of the box structure;

Fig. 6 a similar view showing a slightly different manner of positioning the end clo-

sures or crate ends in place with reference to the battens, and

Figs. 7, 8 and 9 detail perspective views showing slight modifications of the setting-up and holding elements for the component portions of the box or crate.

Referring first to Figs. 1 to 5 inclusive, the body of the box may be said to comprise a bottom shown in the present instance as composed of three slats or members 1, 2 and 3, a back 4 shown as a single piece, a front 5, likewise shown as a single piece, and a top composed of three slats or elements 6, 7 and 8. Grooved battens 9 and 10 are secured to the slats 1, 2 and 3, the ends of the battens being beveled. Similar battens 11 and 12 are employed with the back element 4, while battens of like form, denoted by 13 and 14, are employed in conjunction with the front element 5. Battens 15 and 16 are employed with the top or the slats 6, 7 and 8 which compose the same.

The various battens thus far described are secured to the respective elements with which they are associated by means of nails indicated by 17, which are driven through the metal strips 18 and 19 which overlie the ends of the various elements composing the bottom, back, front and top, said straps being flexible so that the crate elements may be turned up from the collapsed position shown in Fig. 3 to the position shown in Fig. 1.

The ends of the box or crate are denoted by 20 and 21, and are inserted in the grooves in the battens as indicated in Fig. 1 after the parts are brought to the position shown in said figure, or as they are folded up to the position shown in said figure.

In order to hold the box in its assembled position while it is being packed, or after it is open for the purpose of displaying the goods contained in the box or crate, I preferably employ means for temporarily holding and sustaining the parts in their assembled position, such means being readily removable from their engaging position so that the box or crate may be collapsed. To this end I employ two bail-like members each produced from a single piece of wire bent to form. As will be best seen upon reference to Fig. 5, the batten 12 is provided with a notch in its outer face, or that face which stands next adjacent to the element 4,

and the hooked end 22 of the wire 23 is seated in said groove or notch. The opposite end of the wire is provided with a similar hook denoted by 24, the wire being of such length that when the box elements are brought into their upstanding or assembled position, the wire may be thrown downwardly and the hook 24 caused to pass over the upstanding ends of the batten elements 14.

As will be seen upon reference to Fig. 1, a similar wire or sustaining element is employed in conjunction with the batten 11, and when these two sustaining elements are brought to the position shown in said figure, they securely hold the parts in their assembled or set-up condition. It is to be understood that as the back and front are upturned, or, in other words, brought to their upright position, the box ends 20 and 21 will be positioned, and such members act as spacing elements for the vertically disposed battens 11 and 12, and 13 and 14.

The hooks 22 prevent the wires from becoming disengaged, and yet allow the same to be freely turned down to the position shown in Fig. 3 when the body of the crate is in its collapsed or extended position.

The straps 18 and 19 are turned back upon themselves at one end, preferably adjacent the forward edge of the cover, and are threaded, respectively, through eyes or loops 25 and 26. The other ends of the straps are free and of such a length that when the box top is turned down to the position shown in Fig. 2, said ends may be passed through the loops or eyes and then bent back upon themselves and secured in any suitable manner as by nails 27 or by the employment of any standard strap coupling.

It will be noticed upon reference to Fig. 2 that when the straps are secured in place they overlie the hooked ends 24 of the sustaining wires 23 so that the wires cannot slip out of place, and thus the crate is stayed by said wires and they contribute a degree of stability to the box which would not otherwise obtain.

It is not essential that the battens be grooved, but they may be rabbeted, as shown in Fig. 6, and the box ends denoted by 28 placed therein.

While I prefer to secure the sustaining wires to the battens, such construction is not, however, absolutely essential. In Fig. 7, there is disclosed two loop-shaped sustaining elements produced from wire and designated respectively by 29 and 30, said members being pivotally connected to the box and denoted by 31 and turned outwardly and over the upstanding battens for the back and front of the box.

In Fig. 8 a further embodiment or modification of the sustaining wires is illustrated. In this instance, I again employ two sus-

taining or stay elements which are denoted by 32. Each of these elements at its lower end is provided with a hook 33, the cross element of which is seated in a groove formed in the batten, while the upper end is likewise provided with a hook 34 adapted to be thrown over and engage the adjacent up-right batten of the front or back, as the case may be.

In Fig. 9, a still further modification is illustrated. In this instance I employ what may be termed a long loop designated by 35, the ends of the wire from which this loop is formed extending into an opening formed in the vertical batten secured to the back of the crate, such construction forming a hinged connection, so to speak, the forward or free end of the loop being passed over the upper end of the vertically disposed front batten.

In Fig. 8 I have shown the battens which are secured to the front and back of the box as provided with a short groove spaced between the ends thereof, which grooves are adapted to receive a relatively narrow box end 36. This construction will provide additional ventilation by reason of the fact that the narrow box end will not reach to the upper and lower battens when the box top is turned down to its closed position.

It is manifest that the top and bottom may be produced from a single piece or butted pieces.

What is claimed is:

1. In a knock-down crate, the combination of a bottom, front, back and top; means securing said elements together so that they may be turned outwardly into a flattened condition and likewise brought to set-up position; battens secured to the front, the upper ends whereof extend upwardly to a slight extent above the upper edge of the box front; and means pivotally attached to another of the box elements, said means detachably engaging said upwardly extending batten ends and serving to hold the elements together in their set-up position while leaving the top free to be opened or closed.

2. In a knock-down crate, the combination of a bottom, front, back and top; battens secured to each of said elements adjacent each end thereof, the ends of the battens being beveled; means securing the bottom, front, back and top to each other; said means permitting the elements to be laid out in a flattened condition and to be likewise brought to set-up position; and means for sustaining the crate in set-up position, said means comprising a wire located at each end of the crate said wires each having a pivotal connection with one of the crate elements and provided with a bent portion adapted to engage the upper end of an up-standing batten.

3. In a knock-down crate, the combina-

tion of a bottom, front, back and top; flexible metal straps connecting said members; a sustaining wire pivotally connected to one of the box elements to the rear of the front, 5 said wire at its free end being so formed as to engage the front when the crate is in its set-up position; and means for securing the ends of the straps, the straps at such time overlying the free ends of the wires and 10 preventing their disengagement.

4. In a knock-down crate, the combination of a bottom, front, back and top; a batten secured to each end of each of said elements, the ends of the battens being beveled; 15 flexible metal straps securing said elements together; said straps being located one ad-

jacent each end thereof; a loop secured to one end of each strap adjacent the front upper portion of the crate, said loops receiving the opposite ends of the straps to secure the top in its closed position; and a sustaining wire pivotally secured to each of the battens of the back of the crate, said wires at their forward ends being shaped to pass over and engage the upstanding ends of the 20 front battens, said wires being in alinement with the straps whereby the forward ends will be covered by the straps when the ends thereof are secured together.

In testimony whereof I have signed my 30 name to this specification.

JOHN A. MOORE.
